Primary Examiner — Nathan M Johnston(74) *Attorney, Agent, or Firm* — Knobbe, Martens, Olson & Bear, LLP(57) **CLAIM**

The ornamental design for a fluid trap for a respiratory device, as shown and described.

DESCRIPTION

FIG. 1 is a front, top, and left side perspective view of a fluid trap for a respiratory device embodying our new design. FIG. 2 is a front, bottom, and left side perspective view thereof.

FIG. 3 is a top view thereof.

FIG. 4 is a bottom view thereof.

FIG. 5 is a left side view thereof.

FIG. 6 is a right side view thereof.

FIG. 7 is a front view thereof; and,

FIG. 8 is a rear view thereof.

Broken lines are used to illustrate portions of the fluid trap for a respiratory device that form no part of the claimed design.
